I. K. WURDACK

CHAIR

Filed Nov. 11, 1925

Inventor:
Isabelle Kern Wurdack,
Upper Fingland,
Her Attorneys.

UNITED STATES PATENT OFFICE.

ISABELLE KERN WURDACK, OF NORMANDY, MISSOURI.

CHAIR.

Application filed November 11, 1925. Serial No. 68,294.

This invention relates to chairs, and has special reference to chairs for supporting the operator and the work and embodying structure for maintaining the chair parts in proper relationship.

An object of the invention is to provide a work chair comprising a supporting frame, a seat for the operator or worker, in combination with a support for the work movably supported by the frame below the seat and movable to and from positions to afford access to the work carried thereby.

Another object of the invention is to provide an improved portable support for an operator and the work, including a supporting frame, a seat and back for the operator on the frame, in combination with a support for the work mounted in the frame below the seat and movable to and from positions to afford access to the work, and means for strengthening the entire structure so that the work support will be operative irrespective of the strains to which the device is subjected.

Other objects of the invention will appear from the accompanying description, reference being made to the drawing in which—

Fig. 1 is a front elevation of my improved chair.

Fig. 2 is a side elevation.

Fig. 3 is a rear elevation.

Fig. 4 is a cross sectional view through the seat and the work support.

Fig. 5 is a front to rear sectional view through the seat and work support.

My improved chair comprises a supporting frame including four legs 1, of which the two front legs are rigidly connected by a transverse member 2 preferably attached to the front sides of the legs 1 and extending laterally beyond the side edges thereof, so that one end is flush with the outer surface of the vertically wide part 3 attached to the outer sides of one of the front and one of the rear legs; and the other end is flush with the outer surface of a vertically narrow part 4 rigidly connecting the front and rear legs at the opposite side of the chair. The two rear legs are connected by a transverse vertically wide member 5 having its ends in the same planes with the outer surfaces of the members 3 and 4. A relatively narrow transverse strip 6 is attached to and connects the inner sides of the front legs, and a similar transverse strip 7 is attached to and connects the inner sides of the two rear legs. These strips are of equal

width and are of narrower width than the members 2 and 5.

Metallic corner plates 8 are fastened in the upper corners of the frame thus constructed by the bolts 9 whereby the respective frame members 2, 3, 4 and 5 are attached to the legs 1. These devices in cooperation with the seat and back of the chair produce a structure of sufficient strength to resist the strains to which the chair is subjected, whether on level or irregular surfaces, so that the chair can be used as well outdoors upon the ground as indoors upon a floor.

The chair may be constructed as a rocking chair with rockers 10, or not as desired. I prefer to use rockers of wide vertical width as shown, in which case the rockers are attached to the lower ends of the legs by bolts 11, and are preferably seated in notches formed at the lower ends of the legs as shown (Fig. 1).

The seat of the chair as shown is made of a number of transverse slats 12 attached to the end and side frame members 2, 3, 4 and 5, and preferably extending beyond the front, side and rear edges thereof, as will be understood by reference to Figs. 1 and 2.

The back of the chair comprises an upwardly and rearwardly inclined back member 13, preferably possessing a degree of resiliency and having its lower end provided with notches 14 so that the lower end may be fitted closely between the rear legs 1 to utilize the lower end of the back as a part of the strengthening frame of the chair to receive strains to which the legs are subjected when the chair is in use.

A cross connection 15 is secured between the two rear legs in front of the rear surfaces of the legs, and the lower end of the back 13 which is between the legs is attached to said cross connection by bolts 16. The back bears closely against the rear edge of the rear slat 12 and is secured to the rear frame member 5 by screws or bolts 17 and is thereby held in close contact with the rear edge of the slat 12. The upper portion of the seats between the back 13 and the rear frame member 5 contains a filler 18 forming a further rigid abutment for the back, below the slat 12.

To obtain easy portability a handle 19 is attached to the rear side of the back 13 by screws 20 passing through the handle, through the back and into the rear slat 12.

The front and rear legs respectively are 110

connected on their inner sides by transverse slats 21 upon which the movable work support is mounted for movement laterally between the front and rear legs and below the 5 plane of the seat of the chair.

The work support comprises a bottom wall 22 mounted for sliding movements upon the supports 21, vertical side walls 23 arranged to contact with the front and rear legs respectively and being of equal thickness with the cross connections 6 and 7 which hold the work support from upward movement or tilting when the chair is tilted; an inner end wall 24, and an outer end wall 25 of equal 15 thickness with the frame member 4 and arranged to pass thereunder against the legs 1 between the front and rear frame members 2 and 5. The compartment thus constructed may include a partition 26 extending from 20 front to rear and arranged to divide the work materials.

The chair and work support thus constructed has been applied to use and found to meet an existing demand. The user or operator 25 while seated on the chair may move the work support laterally to afford access to the work or contents therein, and the support will be held from tilting when partly withdrawn by the frame parts 6 and 7. By utilizing the 30 various parts of the chair to obtain a strengthening structure as described the chair may be subjected to all the strains of indoor or outdoor use over a long period of time without becoming materially weakened, and 35 without binding the work support. The prevention of the work support from becoming wedged or bound, and therefore difficult to operate, is a beneficial result attained by the

novel and efficient structure described resulting from utilizing the cooperative effect of nearly all of the parts of the chair for this purpose. The construction may be varied within equivalent limits without departure from the nature and principle of the invention. 40

I do not restrict myself unnecessarily, but what I claim and desire to secure by Letters Patent is:—

A chair comprising two front and two rear legs, a seat supported at the upper end of said legs, a transverse slat and a transverse guide attached to the rear sides of the front legs below the seat and having their lower and upper edges parallel and spaced apart, a transverse slat and a transverse guide attached to the rear sides of the rear legs below the seat and having their lower and upper edges parallel and spaced apart, a work support mounted on said guides for sliding movements, front and rear side walls for said support having their upper edges below and adjacent to the lower edges of and in the planes of said slats respectively, an outer end wall attached to said support and having its ends extending beyond said side walls and arranged to extend across portions of the outer surfaces of said legs respectively and having its lower edge extending below said support and constituting a handle, and transverse members attached to the front sides of the front legs and rear sides of the rear legs respectively and having their ends extending laterally beyond said legs and terminating approximately in the plane of the outer surface of said outer end wall. 50 55 60 65 70
